UNITED STATES PATENT OFFICE.

MEYER L. ROBBINS, OF NEW YORK, N. Y.

DESIGN FOR A FINGER-RING OR SIMILAR ARTICLE.

No. 39,247.

Specification for Design.

Patented April 7, 1908.

Application filed January 30, 1908. Serial No. 413,492. Term of patent 7 years.

To all whom it may concern:

Be it known that I, MEYER L. ROBBINS, a citizen of the United States, and a resident of New York, borough of Manhattan, in the county of New York and State of New York, have invented a certain new, original, and ornamental Design for Finger-Rings or Similar Articles, of which the following is a specification.

In the accompanying drawing, Figure 1 is

a view in perspective of a ring having my design applied thereto. Fig. 2 is a view of the same in side elevation.

What I claim is:—

The ornamental design for a finger ring, or similar article, as shown.

MEYER L. ROBBINS.
